UNITED STATES PATENT OFFICE.

FRANK DEROSIER, OF LONG BEACH, CALIFORNIA.

GATE-OPERATING MEANS.

Specification of Letters Patent. Patented Sept. 19, 1916.

1,198,998.

Application filed November 3, 1913. Serial No. 798,920.

To all whom it may concern:

Be it known that I, FRANK DEROSIER, a citizen of the United States, residing at Long Beach, in the county of Los Angeles, State of California, have invented new and useful Improvements in Gate-Operating Means, of which the following is a specification.

This invention relates to a gate operating means.

It is the object of this invention to provide a mechanism for opening and closing slidable gates by means of which the gate may be given a closing movement by manual power and automatically continue to its full closed position.

Another object is to provide means by which a slidable gate will be automatically moved to and be retained in its closed position with means including a sprocket chain carried by the gate and a gear mechanism operable on same whereby the gate may be given an opening movement.

The invention is illustrated in the accompanying drawing, in which:

Figure 1 is a view in side elevation of the gate illustrating same in its closed position. Fig. 2 is a plan view of the operating mechanism as seen on the line 2-2 of Fig. 1. Fig. 3 is a view in elevation of the track end showing one of the gate hangers thereon. Fig. 4 is a detail in plan of the end portion of the track. Fig. 5 is a detail vertical section on the line 5-5 of Fig. 3, partly in elevation.

More specifically, A indicates a fence of any suitable construction provided with a gate-way B and having a beam 2 extending horizontally above the gate opening and for a distance corresponding to the width of the gate opening to one side thereof. Supported on brackets 3 carried by the beam 2 is a track 4 comprising two arched sections having a length approximately equal to the width of the gate 5. One of the arched sections of the rail 4 extends across the gate-way B and the other extending in continuation from the gate-way to the other end of the beam 2. The highest point of each arch is disposed midway of its length with equal gradual curving slopes leading to their points of intersection and to their opposite ends.

Mounted to travel on the track 4 are trolley wheels 6 attached to hangers 7 connecting with the ends of the gate 5; the trolley

wheels 6 being spaced apart a distance corresponding to the length of an arched portion of the rail 4 so that when the gate 5 is in either its open or closed position one of the trolley wheels will be disposed in a depression formed at the intersection of the arched portions of the rail and the other wheel will be positioned adjacent the end of the rail, as illustrated in Fig. 1.

Extending upwardly from the hangers 7 are standards 8 and secured at its ends to the standards 8 and extending therebetween is a sprocket chain 9. The sprocket chain 9 is engaged by a sprocket wheel 10 fixed on a short shaft 11 journaled in a suitable bearing block carried by the beam 2. The shaft 11 is provided with a pinion which is engaged with and adapted to be driven by a gear wheel 13 fixed to a second shaft 14 journaled in suitable bearings carried by the beam 2.

Mounted on the shaft 14 is a crank 15 which is connected to a lever 16 fulcrumed on an upright 17 supported on the beam 2; the connection between the crank 15 and the lever 16 comprising a rod 18. The outer end of the lever 16 is provided with a depending pull rope 19 which passes through a suitable friction claw or catch 20 adapted to engage and hold the rope 19 to maintain the outer end of the lever 16 in its lowermost position in opposition to a weight 21 adjustably mounted on the opposite end of the lever.

In the operation of the invention, when it is desired to open the gate 5 a pull is exerted on the rope 19 to rock the lever 16 and thereby operate through the rod 18 and crank 15 to revolve the gear wheel 13 and thereby rotate the pinion 12, shaft 11 and sprocket wheel 10. The rotation of the sprocket wheel 10 will operate by reason of its engagement with the sprocket chain 9 to shift the gate 5 rearwardly; this movement is continued until the gate is fully opened. The shape of the rails 4 assists in bringing the gate to its fully opened position and in fully closing it.

On operating the lever 16 to open the gate 5 the catch 20 will engage the rope 19 to retain the outer end of the lever 16 in its depressed position with the crank 15 disposed in approximately a vertical position. To close the gate the catch 20 is released whereupon the weight 21 will operate to restore the lever 16 to its normal position and

thereby depress the crank 15 to rotate the gear wheel 13, pinion 12, shaft 11 and sprocket 10 in a reverse direction, thereby causing the gate 5 to advance toward its closed position; the gate 5 gravitating to its full closed position after the trolley wheels 6 have passed the higher points of the arched rails 4.

What I claim is:—

10. 1. A gate operating mechanism, comprising a track having two successive and continuous arched portions, a gate provided with trolleys mounted on said track, a horizontally extending sprocket chain fixedly secured to and carried by said gate, a sprocket wheel meshing with said chain, and means for rotating said sprocket wheel.
15. 2. The combination of a horizontal beam, a track mounted thereon comprising two successive and continuous arched portions, a gate provided with trolleys traveling on said track and spaced apart a distance equal to the length of one arch, a sprocket chain extending horizontally between the trolley wheels, bearings on said beam, a sprocket

wheel mounted in said bearings adapted to engage said sprocket chain, and means for driving said sprocket wheel in either direction to advance the sprocket chain and gate.

3. The combination with a beam, a track 30 mounted thereon comprising two successive and continuous arched portions, and a gate 35 provided with trolleys traveling on said track and spaced apart a distance equal to the length of one arch, of a horizontally extending sprocket chain carried by said gate and extending between the trolleys, a sprocket wheel, a shaft on which said sprocket wheel is mounted, a pinion on said shaft, a gear wheel meshing with said 40 pinion, a rocking lever, and means whereby movement of the lever in either direction will operate to rotate the sprocket wheel which engages the sprocket chain.

In witness whereof I have hereunto set my hand in the presence of two witnesses.

FRANK DEROSIER.
